UNITED STATES PATENT OFFICE.

ROBERT L. McELROY, JOHN E. SHEPHERD, AND JAMES G. NOLEN, OF CHICAGO, ILLINOIS, ASSIGNEES, BY DIRECT AND MESNE ASSIGNMENTS, TO AUTOMATIC FIRE PROTECTION COMPANY, A CORPORATION OF MAINE.

AUTOMATIC FIRE-SIGNAL SYSTEM.

No. 846,836.

Specification of Letters Patent

Patented March 5, 1907.

Application filed December 12, 1903. Renewed July 23, 1906. Serial No. 327,403.

To all whom it may concern:

Be it known that we, ROBERT L. McELROY, JOHN E. SHEPHERD, and JAMES G. NOLEN, of Chicago, in the county of Cook and State of Illinois, have invented certain new and useful Improvements in Automatic Fire-Signal Systems; and we hereby declare that the following is a full, clear, and exact description thereof, reference being had to the accompanying drawings, which form part of this specification.

Our invention has for its primary object to provide an automatic fire-signal system adapted to transmit to a central station a predetermined signal in the event of the existence of undue heat conditions in the area protected by the system.

More specifically one of our objects is to provide a system wherein the circuits and apparatus are so arranged that the occurrence of any one of the usual sources of trouble—such as a breaking, grounding, or crossing of wires in a thermostat-circuit—will cause the transmission to the central station of a "trouble-signal" different from a true fire-alarm signal.

A further object is to so arrange the system that the occurrence of any one of these usual "troubles" and the consequent transmission of a trouble-signal to the central station will not incapacitate the system for subsequently transmitting a further fire-alarm signal in the event of the occurrence of fire within the protected area during the existence of such condition of trouble.

Another object of our invention is to so arrange the system that central-station energy may be employed in its operation.

A still further object of our invention is to so arrange the system that the breaking or grounding of one of the wires of the main or primary circuit or the shunting of the entire current around the protected area, as by a "jumper" across the main-line wires, will not incapacitate the system for causing the transmission to central of an alarm in case of the occurrence of a fire within the protected area.

Other and further objects than those enumerated will be apparent to those skilled in the art from the following description, taken in conjunction with the drawings forming a part hereof, wherein—

Figure 1 is a diagrammatic view illustrating an arrangement of circuits and devices to embody our invention. Fig. 2 is a similar view of a simplified embodiment of our invention, omitting certain features shown in Fig. 1. Fig. 3 is a top plan view of a set of signaling mechanisms such as is employed in equipping a system like that diagrammatically illustrated in Fig. 1. Fig. 4 is a similar view of a signaling mechanism such as is employed in equipping a system like that diagrammatically illustrated in Fig. 2. Fig. 5 is a rear face view of the mechanism illustrated in Fig. 4, the backboard being indicated in dotted lines. Fig. 6 is an end view of the mechanism illustrated in Fig. 4, taken from the lower end thereof. Fig. 7 is a plan detail of a thermostat such as may be employed in conjunction with our system, its casing being shown in section. Fig. 8 is a longitudinal vertical section through one of the thermostat devices. Fig. 9 is a perspective detail of a portion of a thermostat. Figs. 10 and 11 are details illustrating a set of springs employed in the mechanism illustrated in Fig. 3. Fig. 12 is a plan detail of the contact-pens of the "fire-alarm" call-box shown on the left in Fig. 4. Fig. 13 is a similar view of the coating spring-contact members with the pens removed. Fig. 14 is a similar view of the contact-pen of the trouble call-box mechanism shown to the right of Fig. 4. Fig. 15 is a view similar to Fig. 13 of the stationary contact member of said trouble-box. Fig. 16 is an enlarged detail of the trip mechanism for the trouble-box shown to the left in Fig. 5, illustrating the parts in one position. Fig. 17 is a similar view illustrating the parts in another position. Fig. 18 is a fragmentary detail of the ends of the latch-arm which cooperates with the mechanism of the figures just described. Fig. 19 is a detail plan view of a portion of said trip mechanism. Figs. 20 and 21 indicate in two positions the coaction of the trip mechanism shown to the right of Fig. 5 with one end on the latch-lever of the corresponding fire-alarm call-box; and Fig. 22 is a top plan view of the armature of the trip mechanism, showing its relation to said end of the said latch-lever. Figs. 23 and 24 are views similar to Figs. 20 and 21, illustrating the relation of the trip mechanism to the opposite

end of the latch-lever in two positions. Fig. 25 is a view similar to Fig. 23, showing the relation of the trip-armature and the long end of the latch-lever. Figs. 26 and 27 are 5 respectively a top plan view and a longitudinal section through the latch-lever, fragmentarily illustrated in the preceding figures. Figs. 28 to 35, respectively, are diagrammatic views illustrating the operation of our 10 system under the various conditions indicated by the legends written below the respective figures.

Throughout the drawings like numerals of reference refer always to like parts.

15 Referring now to the diagrammatic views, it will be seen that our system contemplates the provision of a normally closed main or primary circuit A, (shown in heavy lines,) energized by central-station batteries C B 20 and including at the central station suitable signal-responsive instrumentalities K and K' and a subcircuit B, local to the protected area or "fire risk," in parallel to a local portion of the main circuit, said subcircuit being 25 itself divided into two parallel legs or branches, between which are connected the thermostats.

The two parallel branches of the local subcircuit B are respectively designated as B^r 30 and B^w and for purposes of distinction will be termed the "red" and "white" sides, respectively, of the subcircuit.

In the portion of the main circuit local to the "risk" or protected area is arranged an 35 electromagnetic device C, controlling an "alarm" signal-box, while in the subcircuit is arranged a normally balanced differential electromagnet D, whose balancing-coils form part of the parallel branches of said subcircuit 40 and which controls the trouble call-box.

A suitable mechanical construction and arrangement of magnet and box devices for carrying out our invention is fully illustrated in Figs. 3 to 6, and these devices will now be 45 described.

The mechanisms illustrated in Figs. 4 to 6 are also shown in Fig. 3 in conjunction with supplementary mechanism for accomplishing a result not attained by the simpler mechanism, and we will first describe those devices common to both embodiments of our invention.

Referring now to Figs. 3, 4, 5, and 6, 1 indicates a backboard whereon are mounted 55 two spring-impelled call-boxes or signal devices 2 and 3 of a well-known type, electromagnetic actuating or trip mechanism for said boxes, and suitable circuit-terminals. The box 2 is provided with a spring-actuated 60 train of gearing and includes a winding-stem 2^a, carrying a stop-screw 2^{aa}, a number-wheel arbor 2^b, projecting above the front face of the box, and a trip-arm-carrying arbor 2^c, projecting from its rear face. The gearing- 65 train is so arranged that the arbor 2^b com-

pletes two revolutions to one of the arbors 2^a and 2^c, the movement of arbor 2^a being limited to one revolution of the stop-screw 2^{aa}, which is arranged to strike some fixed portion of the box-frame after substantially 70 completing a revolution. Similar mechanism is provided in the box 3, like parts to those in box 2 being indicated by numeral 3 with the corresponding exponent letter.

Referring again to box 2, 2^d is a number-wheel carried by arbor 2^b, having upon its periphery the number of teeth peculiar to the station—say five. Associated with said wheel are a spring-pen 5 and its stationary spring-contact 6, normally arranged in contact 8c and adapted to be separated by the passage of the teeth of the wheel 2^d beneath the pen 5.

The mechanism thus described constitutes the "trouble-box," as we will hereinafter arbitrarily term it, the operation of which is 85 controlled by the electromagnet D, through trip mechanisms arranged as follows: d indicates the magnetically-responsive armature of the electromagnet, provided with an arm d', projecting toward the trouble-box. 2^e 90 indicates a latch-arm centrally secured to the arbor 2^b of the trouble-box and provided at its opposite extremities with upturned lips 2^f, whose horizontal paths of rotation intersect the vertical arc of movement of the arm d' 95 of the magnet-armature. The parts are so constructed that when the armature d is held away from the magnet-poles by the tension of the armature-spring it lies in the path of the latch-arm 2^e, as best illustrated in 100 Fig. 16, while when attracted by the magnet D its arm d' is removed from the path of the latch-arm 2^e, as shown in Fig. 17.

The box 3, which we will hereinafter designate the "fire-alarm box," (although under some conditions it acts to transmit trouble-signals) is provided with two circuit-breaking wheels mounted on the common arbor 3^b. One of said wheels 3^d is toothed, with, say, three groups of five (the box-number) teeth each upon its periphery. This is the true fire-signal wheel. The second wheel 3^e occupies a constant position relative to the wheel 3^d and is provided with a peripheral portion of even height with the teeth of the wheel 3^d and of slightly-greater peripheral extent than the toothed portion of the said wheel 3^d, followed (in the direction of its operative rotation) by a group of teeth—say five—to constitute an identifying signal-transmitter. Associated in the usual manner for coaction with the wheel 3^d are the spring-pen 7 and its contact 8, while associated in like manner with the wheel 3^e are arranged the pen 9 and its contact 10. Both 110 of these pen-springs are normally in contact with their respective contact-springs.

The fire-alarm box 3 is arranged for control by the electromagnet C; but its coaction with the trip mechanism thereof is peculiar. 115

Referring now particularly to Figs. 20 to 27, wherein means for effecting such control is shown in detail, c indicates the armature of the magnet C , provided with an arm c' at its end bifurcated to form two vertically and transversely separated fingers c^2 and c^3 , the upper one of which, c^2 , projects in advance of the lower finger c^3 .

3^1 indicates a latch-lever carried by the rear gear-wheel 3^c of the fire-alarm box 3 and disposed in a horizontal plane at a height intermediate the ends of arms c^2 and c^3 of the magnet when the armature is in open position. One end of said lever is shorter than the other and is provided near its end with an upturned stud 3^g , adapted to engage the end c^2 of the magnet-armature when the latter is in open position and to pass beneath the same when the armature is closed, as best illustrated in Figs. 20 and 21. The opposite longer end of the latch-lever 3^1 (which alone is long enough to reach the finger c^3 of the armature) is adapted to pass over the finger c^3 when the armature is in open position and to be engaged thereby when the armature is closed, as best illustrated in Figs. 23 and 24. It will therefore appear that in each position of its movement the armature c is adapted to interrupt the passage of one end only of the latch-lever 3^1 and to permit the passage of the other end of the said lever. Normally the box is set with its lever-stud 3^g in engagement with finger c^2 of armature c , as shown in Fig. 20.

11, 12, 13, 14, 15, 16, and 17 represent binding-posts for electric wiring mounted upon the backboard 1.

The mechanisms thus far described are duplicated in the mechanisms shown in similar positions in Fig. 3.

We will now describe the circuit connections of the parts thus far enumerated, which are common to both embodiments of our invention, with special reference to Figs. 1 and 2.

From central battery C B the main-line circuit may be traced through wire 18, including the register K , to the binding-post 16, thence by wire 19 to the trouble-box pen 5 and its contact 6, thence by wire 20 to the spool 20 e of the electromagnet C , returning by wire 21 to the alarm-box contact-spring 10 and pen 9, thence by wire 22 to binding-post 15, and by line-wire 23 through register K' back to the central battery C B. This constitutes the primary circuit A.

Referring now to the thermostat-subcircuit B, it will be seen that the pen 7 is tied by a wire 24 to the pen 9, and the pen-contact 8 is connected by a wire 25 with a coil 25 e of the electromagnet C , which coil is wound in a direction opposite to that of the coil 20 e as a simple means of balancing the electromagnet C when both the primary circuit and the subcircuit are energized. From the coil 25 e a wire 26 extends to the juncture of the

red and white sides or parallel branches B^r and B^w , respectively, of the thermostat-circuit.

To trace first the red branch B^r of the thermostat-circuit, 27 indicates a connection from wire 26 to a coil 27 d of the electromagnet D. 28 indicates a wire connecting said coil 27 d with the resistance R^r , whence extends a wire 29, terminating at the binding-post 11 upon the board. From said binding-post 11 to the binding-post 14 is looped the red thermostat-wires proper, 30, while from the binding-post 14 a wire 31 is led to and connected with the wire 20 of the main circuit A. To trace now the white side of the parallel, 32 indicates a connection from wire 26 to a coil 32 d of the electromagnet D, wound to secure the opposite magnetic effect to that of the coil 27 d . From the coil 32 d and wire 33 extends to the binding-post 13, whence is looped to the binding-post 12, the wire 34, which forms the white thermostat-wire proper. From the binding-post 12 extends a wire 35, connected to resistance R^w , whose opposite end is connected to the wire 20 of the primary circuit A.

The electromagnets in the circuits described are so wound and adjusted that under normal conditions the magnetizing effect of the current flowing through the coil 20 e of the magnet C is so nearly neutralized by the current flowing through the coil 25 e of the parallel subcircuit B that the armature c is not attracted, while the two branches B^r and B^w of the subcircuit B are exactly balanced as to resistance and as to magnetic effect on the magnet D. Consequently it will be apparent that under normal conditions neither of the electromagnets is magnetically active, but that any variance of the resistance in any circuit or subcircuit will obviously effect the balance of one or the other of the magnets.

Referring now to the refinement particularly shown in Figs. 1 and 3, E indicates an electromagnet, the coil 22 e whereof is included in the wire 22 of the main circuit to be normally energized by the main-line current. e is the armature of magnet E, normally attracted by said magnet and held away from its back contact 40 e . The springs associated with the bell-crank arm e' of the armature of the magnet E are four in number, arranged in pairs, and indicates from top to bottom by the numerals 35 e 35 e' and 33 e . 33 e' The spring 33 e is somewhat longer than its fellows and overlies and makes constant contact with the arm e' of the armature e . Upon such spring 33 e is arranged a piece of insulation 36 e , which is shaped to pass around the spring 35 e and bear against the under side of the spring 35 e . The arrangement of parts is such that normally while the armature e is in forward or attracted position the springs 35 e and 35 e' and springs 130

33^e and 33^{ee} make contact. When, however, the magnet E becomes deenergized, so that the armature-spring withdraws the armature into contact with its rear stop 40^e, the spring 33^e is thereby lifted out of contact with its subjacent fellow and by its insulated connection with spring 35^e lifts the latter from contact with its coacting spring member 35^{ee}. Springs 35^e and 35^{ee} are cut into the white wire 35 of the thermostat-circuit in series therein, while the springs 33^e and 33^{ee} are similarly cut in series into the wire 33 of said white side of the thermostat-circuit. It will be noted, therefore, that when the armature e of the magnet E falls into contact with its back-stop 40^e, lifting the springs 33^e and 35^e out of contact with their normally coacting fellow springs, the effect is to segregate the white thermostat-wire 34, as both the wires 33 and 35 are broken at the springs, as described. The purpose of this segregation of the single thermostat-wire will be hereinafter made apparent.

Collocated upon the backboard 1 with the electromagnet E is a call-box 37, similar in general arrangement to the boxes 2 and 3 heretofore described, and parts whereof are indicated by numeral 37 with exponents like similar parts of box 2. In id box mechanism F indicates an electromagnet. f indicates the armature thereof, adapted when attracted to trip the spring-actuated train of the box 37.

37^d indicates the toothed number-wheel having upon its periphery, say, three groups of five teeth each.

38 indicates the pen associated with said wheel, and 39 the pen-contact spring. These parts are electrically connected as follows: From the back contact 40^e of the armature e of the main-circuit magnet E extends a wire 40, connected to the core 40^f of magnet F. The other terminal of coil 40^f is connected by wire 41 with the pen 38, the contact 39 whereof is connected by wire 42 to the binding-post 17 upon the board. From said binding-post 17 extends wire 43, grounded at its other terminal. To complete the subcircuit to be established through this ground connection, as hereinafter described, wire 44 is led from ground to split the central battery C.B.

We will now describe in general the construction of a thermostat such as is employed in conjunction with our system.

Each thermostat T comprises, essentially, a casing t' of suitable configuration and design, wherein are mounted four flat springs t², t³, t⁴, and t⁵, arranged in pairs, the springs of each pair being arranged end to end and the pairs arranged in parallelism. t⁶ is a rod vertically arranged to pass beneath the pens of springs at the point of separation of the springs of each pair and bearing a suitable weight t⁷. t⁸ is a piece of insulation secured

to the rod and having disposed on opposite ends thereof in position of registration with the openings between the pairs of companion-springs metallic conducting-pieces of wedge shape t⁹ and t¹⁰. Mounted on the upper extremity of the rod in parallelism to the part last described is an inverted-wedge-shaped member of conductive material t¹¹, adapted to bridge across both pairs of springs. The springs t² t³, constituting one pair, are connected in series in one wire 34 of the thermostat-loop, and the pair t⁴ t⁵ are connected in the other wire 30. Under normal conditions the rod t⁶ is secured with fusible material, such as solder or the like, in the position shown in Fig. 8, with the insulation-separated conducting elements t⁹ and t¹⁰ completing the circuits of said thermostat-wires independently through the two pairs of springs. Under such conditions the conducting member t¹¹ of the thermostat is raised above the springs out of contact therewith. It will be apparent, however, that should the fusible material serving to maintain the rod t⁶ in its elevated position be melted the weight t⁷ will cause the rod t⁶ to drop, first removing the conductors t⁹ and t¹⁰ from contact with the pairs of springs to simultaneously break both sides of the thermostat-subcircuit extending therethrough and subsequently (almost instantaneously) bridging the gap with the conducting-bar t¹¹ to close the circuit through both of said pairs of springs and constitute a cross between the thermostat-wires.

It will be apparent that the conditions just described are such as are hardly of possible occurrence from any natural cause, and as the operations just described of simultaneously breaking both of the thermostat-wires and subsequently crossing them is essential to the sending of a true fire-signal the transmission of a false fire-alarm through some ordinary cause, such as the derangement of a circuit or the breaking of a wire, is practically rendered impossible.

Having thus described the physical embodiments of our invention, we will now describe its operation, particularly with reference to the arrangement shown in Fig. 1.

Referring now to Figs. 28 to 35, wherein the wiring of the system is simply illustrated, it will be apparent from an inspection of Fig. 28 (which shows a normal condition of the circuit) that current from central battery C B flowing through wire 23 to binding-post 15 finds a closed circuit through the wire 22, (and coil 22^e of the magnet E,) the pen and contact 9 and 10 of the alarm-box, thence through the coil 20^e, wire 20, pen and contact 6 and 5 of the trouble-box, wire 19 to the binding-post 16, and thence back by wire 18 to the central battery C B. The circuit just traced constitutes the primary or main circuit A. Under normal conditions the

parallel subcircuit B is also closed through both branches and may be traced from wire 22 by wire 24 through the pen and contact 7 and 8 of the alarm-box to wire 25, magnet-coil 25^c, and wire 26, whence it has two paths of equal resistance through the two branches B^r and B^w. Following first the branch B^r, it will be seen that it is closed through the wire 27, coil 27^d, resistance R^r, wire 29, red thermostat-wire 30, wire 31 back to the main-line wire 20. On the other hand, the white branch is closed through wire 32, coil 32^d, wire 33, (including the closed springs 33^e and 33^{ee}), white thermostat-wire 34, wire 35, (including the normally closed springs 35^e and 35^{ee}), resistance R^w back to the main-line wire 20. Under such conditions it will be noted that the magnet E is energized, holding its armature e out of contact with the back-stop 40^e and permitting the group of associated springs to occupy their normal closed positions. The magnets C and D, it will be remembered, being differentially wound and both of the parallel paths through the windings of each being closed are in normal or inactive condition.

The actions following the different troubles against which our system provides will be as follows:

30 *Break in the white wire 34, as indicated in Fig. 29.*—This breaking of the subcircuit B^w stops the flow of current through the coil 32^d and unbalances the magnet D, as the entire current of the subcircuit B flows through the branch B^r thereof, including the coil 27^d of the said magnet. In consequence the armature d of the magnet D is attracted and held by the magnet, releasing the latch-arm 2^e of the trouble-box 2, as indicated in Fig. 17. In 40 consequence the number-wheel of the trouble-box makes two complete revolutions, in each revolution breaking the main circuit A five times at its pen and contact 5 and 6 and transmitting five impulses to the central-station releasing mechanism, as will be well 45 understood. Under these conditions no operative effect is produced upon the magnet C.

50 *Break in the red wire 30^r, as indicated in Fig. 30.*—This break causes the transmission of the same signal as a break in the white wire, as now the entire current of the thermostat-circuit flows through the branch B^w thereof, unbalancing the magnet D and causing the 55 same operation as that last described.

60 *A ground upon the thermostat-circuit, as indicated in Fig. 31.*—Such condition produces the same results as the breaks above described. The main-line circuit is not disturbed, but a preponderating portion of the current of the thermostat-circuit will take a course as follows: through the wire 26, wire 32, coil 32^d, and white wire 33 of the thermostat-circuit to the ground, returning 65 to the battery by ground-wire 44. The pre-

ponderance of current-flow in the winding 32^d of the magnet D unbalances the magnet and attracts its armature, thereby releasing the trouble-box to cause a transmission of a trouble-signal to central, as heretofore described.

70 *A cross or jumper in a thermostat-circuit, as indicated in Fig. 32.*—Such condition unbalances the magnet D, as a path is afforded through subcircuit branch B^w by wire 33 to the cross-wire or jumper (avoiding the resistance R^w) and back to the main line by subcircuit branch B^r through the wire 31, (avoiding resistance R^r). The result is obviously a trouble-signal, as heretofore described, the magnet C being practically unaffected. It will be noted that none of these troubles heretofore adverted to causes the magnet C to attract its armature and trip the alarm-box.

75 *A break in both the thermostat-wires, as indicated in Fig. 33.*—Such a double break in the thermostat-wires cuts off entirely the thermostat-subcircuit B and causes the entire current to flow through the winding 20^c of the magnet C, attracting the armature c and holding it. In consequence the latch-lever 3^f of the fire-alarm box is released, permitting the lever to make a half-revolution until its long end 3^h strikes the finger e³, carried by the armature, as indicated in Fig. 24. During this 80 half-revolution of the lever the wheels 3^d and 3^e make a full revolution. The wheel 3^e lifts pen 9 out of contact with its contact-spring 8 during the entire time of the passage of the number-wheel 3^d under its pen 7. It 85 will be noted that no current flows through the pen 7 under the conditions named, as said pen is included in the thermostat-circuit and no current is at present passing therethrough. The current being interrupted at the pens 9 and 10 during the passage of the peripheral cam of the wheel 3^e, a single long dash is recorded by the registering mechanism at central station, thereby indicating exactly the nature of the trouble, said dash-signal being 90 followed by the proper box-number signal transmitted as the teeth of said wheel 3^e passes beneath pen 9.

95 *A true fire-alarm signal, caused by the fusing of a thermostat.*—As heretofore described, the first action of the thermostat when its fusible material is melted is to break both wires of the thermostat-circuit, thereby causing the tripping of the alarm-box 3 in the manner last above described. Instantly 100 thereafter, however, the circuit through the thermostat-wires is closed by the thermostat member t^h, and a cross between said wires is established. It will be noted that a circuit is 105 re-established through the thermostat-subcircuit as above described with reference to Fig. 32, and the magnet C is accordingly again balanced, so that its spring retracts its armature, thereby restoring the finger e³, carried by 110 the armature, to such position that the end 3^h 115

of the alarm-box latch-lever 3^r may pass thereby, as illustrated in Fig. 23. It will also be noted that the current now flows through the pens 7 and 8 in the subcircuit B.

5 The trouble and alarm boxes 2 and 3, respectively, are preferably so timed that they do not operate upon their pens simultaneously. So, assuming that the trouble box is timed to operate first, the following results 10 ensue from the conditions just described.

The main circuit is first broken at the pen and contact 5 and 6 by the trouble-wheel 2^d sending a round of five to the central station, which is immediately followed by a signal 15 from the alarm-box. Under the present conditions it will be seen that when the pen 9 is lifted by the cam-wheel 3 the main circuit is thereby broken and the entire current caused to flow through the thermostat-circuit, 20 and consequently through the pen 7 and contact 8 in said circuit. As these contacts are broken by the number-wheel 3^e the true fire-alarm signal (three rounds of five) is sent in, followed by another round of five from the 25 wheel 3^d . Both of the wheels being then ready for a second revolution, the foregoing signal is repeated, thus completing a signal which can be in no way confused with any trouble-signal capable of being sent by the 30 boxes. It will be understood, however, that the receipt of the predetermined fire-signal (three rounds of five) under any conditions is assumed to indicate a fire even though the full signal above described is not complete, as 35 the wheel 3^e acts to send its signal only when fire conditions (double break followed by a cross in the thermostat-subcircuit) have occurred.

It will be noted that under any condition 40 of trouble heretofore mentioned the subsequent occurrence of a fire will result in the proper transmission of a true fire-alarm—that is to say, at least the single operative revolution of the fire-alarm wheel 3^e .

45 To refer again to Figs. 29 to 33, in each of which figures an operating-thermostat is included in dotted lines, it will be seen that under the conditions shown in either Figs. 29 or 30—that is to say, the condition of a break in 50 either of the thermostat-wires—the subsequent fusing of a thermostat, as indicated in the dotted lines, will first cause complete severance of the subcircuit B (thereby tripping the alarm-box 3) and the subsequent re-establishment of the path through the subcircuit left by the unbroken thermostat-wire. 55 It follows, therefore, that the alarm-magnet C will be first unbalanced, when all of the current of the main-line circuit flows through 60 the coil 20^e thereof and subsequently balanced again by the completion of the thermostat-subcircuit, including its coil 25^e . Further, it will be seen that under this last-named condition the circuit through the pen 65 and contact 7 and 8 is completed, enabling

the true fire-alarm wheel 3^d to send in its signal of three rounds of five.

Referring now to the condition shown in Fig. 32, when a cross has occurred upon the thermostat-wires it will be apparent that a 70 double break of the thermostat-wires by the fusing of the thermostat T causes the entire current of the thermostat-circuit to flow through the resistance R^e across the jumper or cross and back to the line through the resistance R^w , thereby including said resistances in series and more than doubling the total resistance of the subcircuit. This causes a preponderating flow of current 75 through the main-line coil of the magnet C 80 sufficient to attract its armature, tripping the alarm-box so that it makes one round and causing the transmission to central of a true alarm-signal in the manner heretofore described. In the event that break in both 85 wires has occurred, as indicated in Fig. 33, it will be recalled the fire-alarm box will have been tripped by the magnet C, but will have made but a single revolution, as the armature of magnet C is held in attracted position. 90 The box is accordingly now in condition to make a second revolution of its number-wheels in the event of the restoration of the armature of the said magnet to open position. If now a thermostat is fused, as indicated in dotted lines in Fig. 33, the breaking of both thermostat-wires by the thermostat 95 produces no effect, (as a double break is already present,) but the subsequent cross upon the lines establishes a circuit through 100 the thermostat-wires as follows: through the wires 32, 33, and 34 of the white side of the subcircuit across the thermostat-cross and back by wires 30 and 11 to the main line. This closes the circuit through the coil 25^e of 105 the magnet C, balancing the said magnet so that the spring may restore its armature c to open position. Thereby the latch-lever 3^r of alarm-box 3 is again released, as indicated in Fig. 23, so that the wheels 3^d and 3^e may 110 make their second round. It will be noted that the wheel 3^d breaks the main-line circuit, causing all of the current to flow through the subcircuit B while the teeth of wheel 3^e are passing its pen 9, so that a true alarm of 115 three rounds of five is sent in by the wheel 3^d . The mechanism shown in Figs. 1 and 3 and not found in the simplified circuit of Fig. 2 is provided to the end that should a break of 120 an outside main-line wire or a cross on said wires occur, or a jumper be placed across the terminals of the outside wires, or should all of these "troubles" occur the system is not incapacitated to send in a fire-alarm signal in 125 the event of the fusing of a thermostat in the protected area. It will be noted that under any of the conditions specified all current is cut off from the local portion of both main and sub circuits. Consequently the signaling devices in the said circuits are incapable 130

of transmitting any signals to the central station. It will be noted, however, that the cutting out of the local portion of the main circuit deenergizes the magnet E, which permits the armature e to be retracted by the spring into contact with the back contact-stop 40°, which has a connection to ground through the magnet F and pens 38 and 39 of the auxiliary box 37. The bell-crank arm of the armature e during this operation lifts the spring 33°, thereby, as heretofore described, isolating the thermotsat-wire 34 and connecting it to ground through the path above described. Should now a thermostat become fused in a thermostat-circuit, the double break produces no effect; but the subsequent cross of the thermostat-wires gives a path from the ground through wire 43, binding-post 17, wire 42, pen and contact 39 38, wire 41, magnet-coil 40°, wire 40, contact 40°, armature e to spring 33°, thence by wire 33 to the cross occurring at the thermostat, thence by wires 30 and 31 to the main line 20, and thence by wires 19 and 16 to the central battery, through which it passes to ground by wire 44. The establishment of the circuit just described energizes the magnet F, pulling its armature f and tripping the auxiliary signal-box 37, the number-wheel of which transmits through pen 38 its arbitrary signal—for instance, the true fire-signal of three fives.

While we have herein fully described specific embodiments of our invention which will be found advantageous, we do not desire to be understood as limiting ourselves to exactly the relative arrangement of parts set forth or to the construction of the devices employed in carrying out our system in the manner described.

It will be obvious to those skilled in the art that the system herein set forth is susceptible of various changes and alterations without departing from the principles of our invention, and therefore

What we claim, and desire to secure by Letters Patent of the United States, is—

1. In a fire-signal system, a main circuit including a signal-responsive instrument, a source of supply of electric energy for said circuit, a subcircuit having two branches in parallel to the main circuit, a signal-transmitting device in one of said circuits, an electromagnetic actuating device for said signal device arranged in a portion of the main circuit paralleled by the subcircuit, said actuating device being adapted to become operative on the rupture of the subcircuit, and thermostatic devices in said subcircuit arranged and adapted to simultaneously rupture both branches thereof.

2. In a fire-signal system, a main circuit including a central signal-responsive instrument, a source of current-supply arranged to

energize the main circuit, a subcircuit having two branches in parallel to the main circuit, a signaling device in one of said circuits, an electromagnetic actuating means therefor having its magnet in the portion of the main circuit paralleled by the subcircuit, a second signaling device arranged in one of said circuits, an electromagnetic actuating device therefor having a differentially-wound magnet, one of the coils whereof is included in each branch of the subcircuit, and thermostatic devices common to both branches of said subcircuit.

3. In a fire-signal system, a main circuit including a signal-responsive device, a source of current-supply for said main circuit, a signaling device arranged to break said main circuit and having a coil of its magnet arranged in said circuit, a subcircuit in shunt around said coil including a second coil of said electromagnet, differentially wound with respect to the first coil, said subcircuit having two parallel branches, a second signaling device arranged in one of said circuits, a differentially-wound electromagnetic operating device for said second signaling device, the coils whereof are included in the parallel branches of the subcircuit, and thermostatic devices adapted to break and make connection in both branches of the subcircuit simultaneously.

4. In a fire-signal system, a main circuit, including a signal-responsive device, a source of current-supply for said main circuit, a subcircuit having two branches parallel to the main circuit, signaling devices adapted to transmit signals through the main and sub circuits for actuating said devices comprising an electromagnet included in the main circuit, another signaling device, adapted to send signals through one of the circuits, an actuating device for the last said signaling device comprising a differentially-wound electromagnet, one of the coils whereof is included in each branch of the subcircuit, and thermostats in said subcircuit adapted when fused to first break both thermostat-wires and subsequently reestablish a circuit therethrough.

5. In a fire-signal system, a main circuit including signal-responsive devices, a source of current-supply for said circuit, a subcircuit having two branches parallel to a portion of the main circuit, a signaling device in one of said circuits, electromagnetic actuating means therefor arranged in the portion of the main circuit paralleled by the subcircuit, a second signaling device arranged in one of the said circuits, an actuating device therefor comprising a differentially-wound electromagnet, one of the coils whereof is arranged in each branch of the subcircuit, and balancing resistances arranged in the two branches of said subcircuit.

6. In a fire-signal system, a main circuit, including a signal-responsive device, a source of current-supply in said circuit, a ground connection from said circuit, a subcircuit having two branches parallel to the main circuit, signaling devices and actuating means therefor arranged in said circuits, thermostats in said subcircuit branches, adapted to cross said branches, means for 60 breaking a subcircuit branch to isolate a section of said branch from electrical connection with the other, an electromagnet in the portion of the main circuit paralleled by the subcircuit adapted when energized to maintain said circuit-breaker in inoperative position, a grounded subcircuit adapted to be connected to the isolated section of the thermostat-subcircuit by the action of the circuit-breaker, and a signaling device and 65 operating means therefor operatively associated with said grounded subcircuit.
7. In a signal system, two circuits having portions oppositely disposed so that current may flow therethrough in opposite directions, a common source of supply for said circuits, a means for establishing a cross between the oppositely-disposed portions of said circuits, and signaling instrumentalities associated with said circuits and arranged to 70 be actuated on the occurrence of a cross between such circuits.
8. In a signal system, a source of current-supply, two circuits deriving current from said source of supply and having proximate portions wherein the circuit flows in opposite directions, said circuits having definite relative resistances and the resistances being so disposed that the relation is not preserved in the corresponding portions of the two circuits lying between their proximate portions and the negative terminal of the source of supply, a signaling apparatus responsive to relative variations of current-flow in said two circuits, and means for establishing a 80 cross between the circuits in the proximate portions thereof.
9. In a fire-signal system, a main circuit, a subcircuit having two branches in parallel to a portion of the main circuit, signaling instrumentalities comprising two circuit-interrupters arranged for successive operation, one located in the subcircuit and one in the main circuit, electromagnetic actuating devices arranged and adapted to actuate the 85 circuit-breakers upon an abnormal decrease of current-flow in the subcircuit, and a thermostat arranged and adapted when fused to break both subcircuit branches and then re-establish a current-path through the subcircuit.
10. In a fire-signal system, a main circuit, a subcircuit having two branches in parallel to the main circuit, a signaling instrumentality in the main circuit, actuating device therefor responsive to abnormal decrease in 90 current-flow through the subcircuit, another signaling instrumentality in one of the circuits, an actuating device therefor responsive to relative variations in current-flow through the two branches of the subcircuit, and a thermostat arranged and adapted when fused to break both branches of the subcircuit.
11. In a signal system, in combination with circuits to be supervised comprising two wires, of signal-transmitting means for indicating a break in either wire, other signal-transmitting means for indicating a break in both wires, signal-responsive devices, and suitable circuit connections between said 95 signal-responsive devices and the break-indicating means.
12. In a signal system, in combination with circuits to be supervised comprising two wires, of signal-transmitting means for indicating a variation in the relative current-flow through said two wires, another signal-transmitting means for indicating a cessation of current-flow in both of said wires, signal-responsive devices and suitable circuit connections between signal-transmitting means and the signal-responsive devices.
13. In a fire-alarm system, a main circuit, a subcircuit, an electromagnetic signaling apparatus comprising an actuating-magnet 95 responsive to rupture of the subcircuit, and a normally set signal device associated with the magnet to be actuated thereby when the subcircuit is ruptured and again actuated when the subcircuit is reestablished, said signal device comprising two sets of signaling-pens, one in the subcircuit and one in the main circuit, signal-responsive devices in the main circuit, a battery in said main circuit, and a thermostat in the subcircuit adapted 100 when fused to first rupture said subcircuit and then reestablish it.
- In testimony that we claim the foregoing as our own we affix our signatures in presence of two witnesses.
